UNITED STATES PATENT OFFICE.

ALBERT GROSSMANN, OF BROOKLYN, NEW YORK.

HYDRAULIC-PRESSURE REGULATOR FOR CANE-MILLS.

No. 831,786.

Specification of Letters Patent.

Patented Sept. 25, 1906.

Application filed June 7, 1905. Serial No. 284,134.

To all whom it may concern:

Be it known that I, ALBERT GROSSMANN, a citizen of the United States, and a resident of the borough of Brooklyn, in the county of 5 Kings and State of New York, have invented certain new and useful improvements in Hydraulic-Pressure Regulators for Cane-Mills, of which the following is a specification.

This invention relates to hydraulic-pressure regulators for cane-mills and the like. Its organization comprises means for automatically regulating the distances between the surfaces of rolls in mills, so that they may easily adjust themselves to various thicknesses of material that may pass between them and maintain a constant pressure on said material. It is also characterized by means for controlling and varying the distances that the rolls can be separated or 20 made to approach each other.

The invention is exemplified in the accompanying drawings, in which—

Figure 1 represents a front elevation and section of a housing for a mill as on the line $x x$ of Fig. 2, with the invention connected therewith. Fig. 2 shows a top view of Fig. 1. Fig. 3 is an enlarged partial section of Fig. 1 as on the line $x' x'$. Fig. 4 represents an enlarged portion of Fig. 1.

Housings are represented at A, with side rolls B B² and the top roll B', supported, respectively, on the side shafts C C² and the top shaft C', which shafts are connected by the gears b b² b' in the usual manner. The side shafts C and C² are supported in the housings on the side-roll bearings D and D², and the top shaft C' is supported in the bearings D'. Caps E maintain the top shafts C' with their bearings in proper position. Caps F coact 35 with the shaft C, and the caps G coact with the shaft C². The cap G has extending therefrom inclined surfaces g, against which bear wedge-bolts H for adjusting the location of the shaft C² of the roll B².

Each of the caps F has formed therewith a cylinder F', in which a plunger I operates. The latter has the shoulder I' and the spherical end bearing-surface I², to which latter is adjustably fitted the bearing-plate J, by 45 means of the bolt J', the said bolt being somewhat smaller in diameter than the opening j, through the plate J, so that the latter can adjust itself in different positions. A stud J³, with jam-nuts J⁴ and spring J⁵, is secured to 50 the plate J as a secondary support to hold it

up in place. A cup-leather packing-ring K is held in place on a shoulder of the plunger I, with the follower-plate K', the latter bearing on a shoulder i of the plunger. Piping F² extends from an opening through the cap F 60 for the introduction of a fluid to exert pressure against the face I² of the plunger I. The said pressure is maintained by an accumulator connected with the piping F². (Not shown.)

On the forward end of the plunger I there is an adjustable stop consisting of the adjustable sleeve M, which has formed on its outer cylindrical surface the threads m, which are preferably multiple threads that mesh with 70 corresponding threads in the cap F. The forward end of the sleeve M terminates in a spur-gear M', which meshes with a pinion N, fastened on a spindle N'. The spur-gear M' has extending from it a projecting collar m'. 75 The spindle N' has a bearing n in the cap F, the threaded portion n², which operates through a stationary nut O, fastened to the said cap F, and a squared end n³. An index-plate P is fastened to the stationary nut O, 80 and a collar Q, with an index thereon, is fastened to the spindle N'. The pitch of the threaded portion n² bears the same relation to the lead of the threads m that the pitch diameter of the pinion N bears to the pitch diameter of the gear M', and if the threaded portion n² is right-handed the threads M are left-handed, or vice versa, by which disposition the pinion N and spur-gear M' are always maintained in mesh with each other.

To use the invention, the material is fed to the rolls in the usual manner, and the location of the stroke or action of the plunger I is adjusted by the location of the stop or sleeve M, which controls the movements of the 95 plunger in two directions along its axial center line. The location of the sleeve can be delicately adjusted by means of the pointer P and the index on the collar Q by turning the spindle N'; with the application of a 100 wrench on the squared end n³ of the said spindle. The material passing between the rolls B and B' tends to force the plunger in the direction of the arrow, and is limited to the distance between the face of the projecting collar m' and the face J² of the bearing-plate J. The pressure on the face of the plunger from the regulator tends to force the plunger in the opposite direction to the arrow. The stroke of the plunger is controlled 105 110

and limited by the end faces of the sleeve M, the shoulder I' of the plunger striking against the said sleeve on one side and the face J² of the plate J striking the other side of the sleeve. If the sleeve M is brought to bear against the face J² of the plate J, the fluid in the piping F² cannot act as a cushion for plate J, and in case the hydraulic regulator is not to be used the sleeve M is brought to this position, thereby making a solid backing for the bearing of the shaft. This function of the invention allows the device to be used without the pressure of the accumulator against the plunger. After the sleeve M has been adjusted and located the fluid-pressure from the accumulator is permitted to act through the piping F to bear against the plunger I and the rolls are ready for use. It is evident that the roll B² and the roll B' could each have a similar hydraulic regulator connected up with them or that the said regulator could be connected up with any one of said rolls alone.

The invention could be modified by not forming a thread on the spindle N', and the pinion and the spur-gear may be kept in mesh by making the teeth of one of said wheels with a much longer face than the other.

Having described my invention, I claim—

1. In a hydraulic pressure-regulator for rolls the combination of a cylinder, a plunger therein, means to bring a fluid-pressure against the face of the plunger, a roll located to have pressure brought on it by the said plunger, and means to vary the location of the stroke of the plunger.

2. In a hydraulic-pressure regulator for rolls the combination of a cylinder, a plunger therein, means to bring a fluid-pressure against the face of the plunger, a roll actuated by the pressure against the face of the plunger, an adjustable stop for the plunger, means to adjust the location of said stop to control the movements of the plunger.

3. In a hydraulic-pressure regulator for rolls the combination of a cylinder, a plunger therein, means to bring a fluid-pressure against the face of the plunger, a roll actuated by the pressure against the face of the plunger, an adjustable sleeve around the plunger, means on the plunger arranged to bear against and be stopped by the end faces of the said sleeve.

4. In a hydraulic-pressure regulator for rolls the combination of a cylinder, a plunger therein, means to bring a fluid-pressure against the face of the plunger, a roll actuated by the pressure against the face of the plunger, a sleeve on the roll, and a stop for the plunger arranged to control its movements in two directions.

5. In a hydraulic-pressure regulator for rolls the combination of a cylinder, a plunger therein, means to bring pressure against the face of the plunger, a roll actuated by the

pressure against the face of the plunger, a sleeve on the plunger, means on the plunger arranged to bear against the end faces of the sleeve, a spur-gear extending from the sleeve, a spindle adjacent to the plunger, means to turn the spindle, and a pinion on the spindle meshing with the gear on the said sleeve.

6. In a hydraulic-pressure regulator for rolls the combination of a cylinder, a plunger therein, means to bring pressure against the face of the plunger, a roll actuated by the pressure against the face of the plunger, a sleeve on the plunger, means on the plunger arranged to bear against the end faces of the sleeve, a spur-gear extending from the sleeve, a spindle adjacent to the plunger, a threaded portion on the spindle, a stationary nut meshing with the said threaded portion, means to turn the spindle, and a pinion on the spindle meshing with the gear on the sleeve.

7. In a hydraulic-pressure regulator for rolls the combination of a cylinder, a plunger therein, means to bring pressure against the face of the plunger, a roll, a shaft for the roll, a side bearing supporting the shaft and located to be acted upon by the plunger, a sleeve around the cylindrical surface of the plunger, a shoulder on the plunger arranged to bear against one side of the said sleeve, an adjustable bearing-plate connected with the plunger to bear against the other side of the sleeve, a spur-gear extending from the sleeve, a spindle adjacent to the plunger, a pinion on the spindle meshing with said spur-gear, a threaded portion on the spindle, a stationary nut meshing with the said threaded portion, means to turn the spindle, an index carried on the spindle, and a stationary pointer arranged to coact with the index, a thread on the sleeve arranged to mesh with a stationary thread.

8. In rolls the combination of a housing, rolls in the housing, a cap for each roll, a cylinder formed in one of said caps, a plunger in said cylinder, a bearing-plate adjustably connected with the plunger, an adjustable sleeve around the plunger, threads on outer surface of the sleeve meshing with corresponding threads in the cap containing the said cylinder, a spur-gear extending from the sleeve, a spindle supported at one end in a bearing of the cap containing the plunger, a stationary nut secured to the latter cap, a threaded portion of the spindle fitting said nut, a pointer extending from said nut, an index on the spindle arranged to coact with the pointer, a squared end for the spindle to turn the latter, and piping extending from the cap leading into the cylinder.

9. In combination with rolls, of a hydraulic-pressure regulator to control the location of one of said rolls, a plunger in said regulator to bring pressure on said rolls, means to control and adjust the movements of said plunger,

wedge-bolts to adjust the location of another of the rolls, and means to bring a fluid-pressure against the face of the plunger.

10. In a hydraulic-pressure regulator for 5 rolls the combination of a cap, a cylinder therein, a plunger in the cylinder, means to bring pressure against the face of the plunger, a roll, a shaft for the roll, a side bearing supporting the shaft and located to be acted 10 upon by the bearing-plate, a sleeve around the cylindrical surface of the plunger, a shoulder on the plunger arranged to bear against the said sleeve, a bearing-plate adjustably connected with the plunger and ar- 15 ranged to bear against said sleeve, a spur-

gear extending from the sleeve, a spindle supported in the cap, a pinion on the spindle meshing with the spur-gear, a left-handed thread on the spindle, a stationary nut meshing with said thread, a right-handed thread 20 on the sleeve meshing with a thread in the cap.

Signed at the borough of Brooklyn, in the county of Kings and State of New York, this 2d day of June, A. D. 1905.

ALBERT GROSSMANN.
